UNITED STATES PATENT OFFICE

91,897

DESIGN FOR A SCORE KEEPING DEVICE

Fred L. Paul, Fort Wayne, Ind.

Application January 16, 1934, Serial No. 50,419

Term of patent 3½ years

To all whom it may concern:

Be it known that I, FRED L. PAUL, a citizen of the United States, residing at Fort Wayne, in the county of Allen and State of Indiana, have invented a new, original, and ornamental Design for a Score Keeping Device, of which the following is a specification, reference being had to the accompanying drawing, forming part thereof.

I claim:—

The ornamental design for a score keeping device as shown.

FRED L. PAUL.
